CLAMP FOR CLAMPING CONCRETE FORMS

Albion H. Jennings and Herbert E. Sharman,
Miami, Fla.; said Jennings assignor to said
Sharman

Application August 3, 1950, Serial No. 177,458

1 Claim. (Cl. 144—291)

1

This invention relates to concrete forms and more particularly to the clamps which are used in clamping together the forms or form boards used in the construction of concrete walls, beams, lintels or the like.

An important object of the invention is to provide a clamp of this type which may be readily and easily operated to clamp the forms or form boards, the clamp securely holding the forms or form boards spaced apart during the setting of the concrete or plastic material used with the forms.

Another object of the invention is to provide a clamp used in clamping concrete forms or boards, which clamps are adjustable so that they may be effectively used in the construction of walls, beams or lintels of various widths and sizes.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

Referring to the drawings:

Figure 1 is a vertical sectional view through the upper portion of a section of a concrete wall and form boards, the clamp forming the subject matter of the present invention being shown in elevation.

Fig. 2 is a fragmental elevational view of the clamp.

Fig. 3 is a fragmental end elevational view of the clamp, the clamp being shown in its open position.

Fig. 4 is a perspective view of the lever bar of the clamp.

Fig. 5 is a perspective view of one arm of the linkage used in connecting the operating lever to the upper bar of the clamp and one of the side bars of the clamp.

Fig. 6 is a perspective view of the pivoted link connected between the lever and upper section of the clamp.

Fig. 7 is an end elevational view of a modified form of the invention.

Fig. 8 is a disassembled view illustrating the levers that connect with one of the clamping side members of the modified form of clamp.

Fig. 9 is a fragmental elevational view illustrating the movable section of the clamp as in its open position.

2
Fig. 10 is a sectional view taken on line 10—10 of Fig. 7.

Referring to the drawings in detail, the reference character 5 indicates the upper portion of a section of wall under construction and to which the mold form boards and clamp, forming the subject matter of the present invention, are secured in the formation of another course of a wall.

10 The reference character 6 indicates form boards, which may be of any desired length, the boards being positioned against the sides of the wall section 5 adjacent to the upper edge thereof, as shown by Fig. 1 of the drawings. The clamp forming the subject matter of the present invention comprises a stationary leg 7 and a horizontal bar 8 welded to the upper end of the leg 7, the bar 8 being preferably of angle bar construction.

20 Secured to the horizontal bar 8, and depending therefrom, are adjustable stops 9 and 10, the stop 9 being spaced from the inner edge of the leg 7 to contact with the form board 6 associated therewith, the clamp 9 being moved to closely engage the form board 6. The stop 10 which is also adjustable, is carried by the bar 8 adjacent to the opposite end of the bar 8, where it cooperates with the movable leg 11 of the clamp, in clamping the form board 12 associated therewith.

30 The reference character 13 indicates a lever of bell-crank construction, which lever is pivotally connected with the horizontal bar 8, at one of the openings 14 thereof by means of pivot pin 14'. The wing nut 15' is positioned on the bolt 12' and affords means for readily securing the bolt in its adjusted positions within an opening of the bar 8. Pivotally connected to one arm of the bell-crank lever 13 at 16, is the operating or control lever 15.

35 The control lever 15 is also pivotally connected to the movable leg 11 at 17, to the end that as the lever 15 moves downwardly from the position shown by Fig. 3 of the drawings to the position shown by Fig. 1 of the drawings, the movable leg 11 will be moved into clamping relation with the form board 12, and as the pivot point 16 moves past dead center with respect to the pins 16 and 14', the movable leg 11 will be held against the form board 12 and since the stop 18 carried by the control lever 15 engages one edge of the movable leg 11, further movement of the leg 11 will be prevented.

40 The operating or control lever is also provided with an upstanding section 18', providing a handle by means of which the lever may be operated.

45

50

55

It is obvious that when the lever 15 has been moved to the position shown by Fig. 1 of the drawings, a stop in the form of the bar 19 is positioned on the lever 15 engaging between the upstanding section 18' of the lever and movable leg 11, thereby holding the lever against accidental displacement. It might be stated that in the use of this device, a pair of these clamping members may be provided for holding or supporting form boards, in which case the operating or control levers 15 of the clamping sections may be connected by the upstanding sections 18' and bar 20, connecting the upstanding sections 18'.

When the clamp has been properly operated to support the form boards, the concrete material may be poured therebetween and allowed to set, after which the form boards may be removed from the finished wall.

In the form of the invention as shown by Fig. 7, the clamp comprises the stationary clamp leg 21 to the upper end of which is secured the supporting bar 22 formed with a plurality of spaced openings 23 to receive the pivot pin 24 used in connecting the pivoted leg 25 of the clamp to the supporting bar 22. By moving the pin 24, it is obvious that the width of the clamp may be varied to meet various requirements.

The pivoted leg 25 is formed with an offset portion 26 which is designed for positioning over a rafter which may be in place where the lintel is to be poured.

In this form of the invention clamps 27 are used as stops against which the leg sections of the clamp engage, restricting movement thereof in one direction.

The reference character 28 indicates a link pivotally connected to the pivoted leg 25, by means of the pivot pin 29, the link 28 being pivotally connected with the lever 30, by means of the pivot pin 31. The lever 30 is also pivotally connected with the supporting bar 22 by the pivot pin 32.

With this form of the invention it is obvious that when the lever 30 is moved beyond the position shown by Fig. 9 of the drawings, to the position shown by Fig. 7 of the drawings, the pivoted

leg 25 of the clamp will be moved to its clamping position against form boards, to hold the form while concrete is being poured thereinto.

From the foregoing it will be seen that due to the construction shown and described, we have provided a clamp for clamping form boards in the construction of concrete beams, walls or lintels, the clamp being such that it will support the form boards thereof over their entire widths, the form boards and clamp being readily removable for dismantling the form, when it is desired. It will also be seen that the form boards may be readily supported in the formation of a mold, the clamps acting to hold the form boards upright.

Having thus described the invention, what is claimed is:

A form clamp for concrete work, comprising a stationary leg, a horizontal bar secured at one of its ends, to the upper end of said stationary leg, stops mounted on the horizontal bar extending below said bar, said stops being adjustable longitudinally of said bar for engaging the form boards, a movable leg, means for pivotally connecting the movable leg to said horizontal bar, a bell-crank lever pivotally connected with the horizontal bar through a bolt passing through the bell-crank lever and horizontal bar, a control lever pivotally connecting the bell-crank lever to the movable leg, and means for limiting movement of the control lever and bell-crank lever in one direction.

ALBION H. JENNINGS.
HERBERT E. SHARMAN.
